these conditions they did not change the total phosphite conversion level very much.

It has been found that dimethyl hydrogen phosphite (DMHP) when pyrolyzed initially forms no appreciable amount of phosphates. As the pyrolysis reaction proceeds, substantial amounts of material which analyzes in aqueous solutions as monomethyl phosphite (MMHP) and H_3PO_3 form. Consequently as the pyrolysis is continued these are converted into more undesired products, phosphates and phosphines. Accordingly, it is beneficial to add methyl phosphate esters at some stage of the pyrolysis for conversion of phosphites to the desired phosphonate derivatives.

In the examples given in the Table I, extraneous phosphate esters were added to the phosphite pyrolysis feeds to ascertain the specific affects of the phosphate esters. In an improved embodiment, the present invention contemplates the production of dimethyl phosphate along with dimethyl phosphite by judicious addition of $POCl_3$ to the PCl_3 feed to methanol to form such a mixture.

Another embodiment of this invention involves the addition of trimethyl phosphate or similar ester to the reaction mixture in the pyrolysis of dimethyl hydrogen phosphite at the proper time for obtaining maximum yield.

In the staged recirculating pyrolysis of DMHP this invention envisions the addition of the methyl ester to a point near the end of the pyrolysis. For example in an apparatus containing two circulating units the ester is added to the effluent before or during addition of the effluent to a final pyrolysis state.

The use of methyl esters such as trimethyl phosphate does not exclude the use of BF_3 or other such catalysts. In fact where trimethyl or dimethyl phosphate is added to DMHP in a pyrolysis reaction, BF_3 may also have been added. One attractive process involves the use of BF_3 to catalyze the desired reactions at the beginning and the addition of methyl phosphates to give better yields during the last half of the reaction when large amounts of unconverted phosphites such as monomethyl phosphite and H_3PO_3 are present.

In staged pyrolysis such as that above it is advantageous to use methyl phosphates in the higher temperature, second stage. BF_3 is especially beneficial at lower temperature early stages.

Study of the action of tri- or dimethyl phosphate on phosphorous acid indicates that ester interchange may occur. This concept does not limit the invention, however, and is not meant to indicate that mono- or dimethyl phosphite is essential to the production of methane phosphonic acid derivatives.

While trimethyl phosphate is a more desirable methylating agent, it costs more than di- or monomethyl phosphate. On the basis of equal methyl content it may be no more desirable. One view holds that the last methyl, i.e., the one visualized as held by the weakly acid POH , is the reactive one. On this basis the trimethyl phosphate has two methyls in reserve but the active methyl is the same as or similar in activity to that in mono-

methyl phosphate. This concept is not to be construed as limiting the invention.

The temperature required for the above-discussed methylations ranges between an upper limit of about 350° C. and a lower limit determined by that resulting from spontaneous reaction of the cold reagents. It is believed that 100° C. to 275° C. is a preferred operating range. The amounts of methylating agents used is of course influenced by many considerations including the feed composition, catalyst, temperature and the economics of the particular reaction. Excess trimethyl phosphate of course would give the maximum yield and fastest reaction according to the present interpretation of the data.

Phosphates are desirable agents since present processes for phosphite pyrolysis include systems for handling these pyrolytic products. Borates are attractive because of the possibility that they might be regenerable with methanol treat to give volatile trimethyl borate.

In special cases other methyl esters might be more desirable.

It is envisioned that mixtures of methyl esters might be especially interesting. Methyl chloride in methyl phosphate or borate is suggested.

Products of this invention may be employed in preparing fuel, lubricating oil, and grease additives, detergents, fire retardants, insecticides, and plasticizers. The methane phosphonic acids undergo reaction with alcohols, esters, salts, bases, as well as with halogens and non-metallic halides.

In addition to the preceding ideas many others will now be obvious to those skilled in the art.

The invention described is claimed as follows:

1. Process for preparing a methane phosphonate which comprises reacting a phosphorous compound selected from the group consisting of phosphorous acid and methyl esters thereof with a methyl ester of a phosphoric acid.

2. Process for preparing a methane phosphonate by reacting a phosphorous acid and a methyl ester thereof with a methyl ester of a phosphoric acid.

3. Process for preparing a methane phosphonic acid and methyl esters thereof which comprises reacting a phosphite with a methyl ester of a phosphoric acid.

4. Process for preparing a methane phosphonic acid and a methyl ester thereof which comprises reacting a phosphorous acid with a methyl ester of a phosphoric acid.

5. Process for preparing methane phosphonic acid and a methyl ester thereof which comprises heating a mixture containing phosphorous acid and mono-methyl phosphite with a mixture containing mono- and dimethyl phosphate to temperatures in the range of 100° to 350° C.

6. Process for preparing a methane phosphonic acid and methyl esters thereof which comprises heating a mixture containing phosphorous acid and mono-methyl phosphite with trimethyl phosphate to temperatures in the range of 100° to 350° C.
